UNITED STATES PATENT OFFICE.

FREDERICK H. UMHOLTZ, OF OKLAHOMA, OKLAHOMA.

APPARATUS FOR RAISING WATER.

1,215,221.

Specification of Letters Patent. Patented Feb. 6, 1917.

Application filed January 15, 1915. Serial No. 2,447.

To all whom it may concern:

Be it known that I, FREDERICK H. UMHOLTZ, a citizen of the United States, residing at Oklahoma, in the county of Oklahoma and State of Oklahoma, have invented new and useful Improvements in Apparatus for Raising Water, of which the following is a specification.

The invention relates to water elevators, 10 and more particularly to the class of water raising apparatus.

The primary object of the invention is the provision of an apparatus of this character wherein water from a well, stream or 15 the like can be trapped so that the same will be raised for its discharge under the action of compressed air; the water when being raised is designed to automatically control the compressed air supply to the water containers forming the traps therefor to assure 20 a continuous discharge of water from the said apparatus when its delivery faucet is open.

Another object of the invention is the 25 provision of an apparatus of this character wherein a novel form of water actuated motor is employed to automatically control the supply of compressed air used for raising the water whereby it may be discharged 30 or delivered from the apparatus.

A still further object of the invention is the provision of an apparatus of this character wherein its construction is of novel form to effect the perfect and accurate working thereof.

A still further object of the invention is the provision of an apparatus of this character which is simple in construction, reliable and efficient in operation, strong, 40 durable, possessing a minimum number of parts, and also which is inexpensive in manufacture.

Other objects will be in part obvious and in part hereinafter pointed out.

The invention accordingly consists in the features of construction, combination of elements and arrangement of parts which will be exemplified in the construction hereinafter set forth, and the scope of the application of which will be indicated in the following claim.

In the drawings:

Figure 1 is a sectional view through a well showing in side elevation the apparatus constructed in accordance with the invention installed for use.

Fig. 2 is a fragmentary elevation looking in the direction of the arrow in Fig. 1.

Fig. 3 is an enlarged fragmentary side elevation of the motor and valve mechanism, 60 the casing of the motor being partly broken away.

Fig. 4 is a top plan view thereof.

Fig. 5 is a sectional view on the line 5—5, looking in the direction of the arrow, of 65 Fig. 4.

Fig. 6 is a sectional view on the line 6—6 of Fig. 4, looking in the direction of the arrow.

Like characters of reference indicate like 70 parts throughout the several views in the drawings.

Referring to the drawings in detail, A designates a water well and B the platform, which has a removable section C closing the 75 upper end of the well as usual, while installed for use in raising water from the well is the apparatus hereinafter fully described.

The apparatus comprises a pair of spaced 80 parallel vertical water containers or receptacles 10 and 11, respectively, forming traps which are suitably supported within the well A in proximity to its bottom, each trap being formed with an inlet opening 12 in 85 its bottom, and this opening is closed through the medium of an inwardly swinging flap valve 13 of any approved type, so that on the entrance of water into the trap the valve will become closed to prevent the 90 discharge of water through the opening 12 in its bottom. In order to produce a continuous flow of water from the apparatus the two traps 10 and 11 are employed, and any number of the same may be used, these 95 traps being submerged in the water supply as usual. For emptying the receptacles or traps 10 and 11, each is provided at its lower end with a short outlet pipe connection 14, these connections being cast integrally and connected to the lower end of a single pipe 15 which extends upwardly through the well A and leads to a suitable point of delivery. Each pipe connection 14 is provided with a check valve 16 to prevent 100 back flow of water into its respective receptacle or trap, and the upper or delivery end of said pipe 15 is provided with a valve 17 to control the delivery or discharge of water therefrom.

The openings 12 in the bottoms of the receptacles or traps 10 and 11 are large enough 110

to allow the same to fill quickly with water when not under air pressure.

Arranged exteriorly of the well A and supported upon the platform B is a reservoir or tank 18 for receiving compressed air from any suitable source, in this instance the compressed air being supplied from any approved form of pump 19 which is suitably connected with the tank.

10 For controlling the supply of air admitted to the receptacles or traps 10 and 11, there is arranged in the delivery pipe 15 a lobe motor or gear motor which comprises a casing 20 having arranged therein the lobe or 15 gear wheels 21 which are in mesh with each other and are fixed to shafts 22 journaled in the casing 20, one of the shafts being extended without the same and is provided with a gear pinion 23 which in turn meshes 20 with a larger gear wheel 24 on the stem 25 of a revolving valve 26 which is mounted in a suitable casing 27. For convenience of construction, the motor casing 20 and the valve casing 27 may be cast integrally, as 25 shown.

Leading from the tank or reservoir 18 is an air supply pipe 28 having branches 29 leading through the valve casing 27 to the receptacles or traps 10 and 11, respectively.

30 The valve 26 within the casing 27 is ported to allow admission of air to one receptacle or trap while the other is exhausting. In Fig. 6 of the drawings the valve is shown in full lines with one port in position to admit air through one branch 29 to the receptacle or trap 10, and by dotted lines the other port in the said valve is in position to allow the exhaust of air through the other branch 29 from the receptacle 11, the outlet 35 or discharge ports 30 being provided for this purpose to exhaust the compressed air to the atmosphere alternately on the working of the valve 26 in its casing 27 when the apparatus is in operation.

40 It will be noted in this instance that there are two admissions and two exhausts of air from each of the receptacles 10 and 11 forming the trap for the water during each revolution of the valve 26, but the arrangement 45 of the parts in said valve to allow any other number of admissions or exhausts may be left to the discretion of the designing engineer of the apparatus.

When no water is allowed to deliver 50 through the pipe 15 the parts of the motor and valve are passive, but by opening the valve 17 in the delivery pipe 15 the flow of water through the motor revolves the valve 26, allowing the air from the tank or reservoir 55 60 to empty the receptacles or traps 10 and 11 alternately.

By arranging proper "lap" of the parts in the valve 26 and admitting air to one

chamber slightly in advance of cutting off the air supplied to the other, an uninterrupted flow of water upwardly through the delivery pipe 15 is obtained, and there will be no tendency of the apparatus to irregularly deliver water on neutral points, or fail to start when the valve 17 is opened.

To avoid the waste of air from the reservoir or tank the apparatus can be so arranged and adjusted that each of the receptacles or traps 10 and 11 may be completely filled with water before air is admitted thereto from the said reservoir or tank and before all of the water is forced from either of the chambers. When the parts have been arranged and adjusted no air will be allowed to pass up the delivery pipe 17 through the motor.

Arranged within the pipe 28 is a pressure relief valve 31 which may be used in the said pipe to limit the air pressure supplied to the receptacles or traps.

It will be apparent that the water when raised will operate the motor which directly controls the valve for the admission and exhaust alternately of air to and from the receptacles or traps 10 and 11, the air being supplied from the reservoir or tank hereinbefore described.

From the foregoing description, taken in connection with the accompanying drawings, the construction and manner of operation of the device will be clearly understood, and therefore a more extended explanation has been omitted.

What is claimed is:—

An apparatus of the character described comprising a pair of water containers adapted to be lowered within a water well spaced from its bottom and having valved inlets, a compressed air tank adapted to be located exteriorly of the well, a water discharge pipe common to said containers, a gear casing arranged in said discharge pipe, gear wheels journaled in the casing and meshing with each other, a valve casing connected with the gear casing and having dual communication with the compressed air tank, the said valve casing having a pair of exhaust ports, branch air supply pipes leading from the valve casing to the container, and a valve within the casing having driven connections with one of the gears in the gear casing and adapted to alternately allow admission of air to one receptacle and the exhausting of air from the other receptacle.

In testimony whereof I affix my signature in presence of two witnesses.

FREDERICK H. UMHOLTZ.
